(54) **TEETH, PREVENTING DECAY**

(76) Inventor: **m Horace H. Hayden**

Horace H. Mayden.
Letters Patent.

The Schedule referred to in these Letters Patent, and making part of the same, containing a description in the words of the said Horace H. Mayden himself, of his improvement, being a remedy, or preventive, for the caries, or decay, of the human teeth, and the diseases, consequent thereto, and to the human mouth.

The pyroliqueous acid, and pyroliqueous, or empyreumatic oil, (tar or balsam) obtained from the distillation of wood (or other vegetable substances of whatever kind and even from common wood root) is, when properly used, or applied, a sovereign preventive or remedy, against the caries, or decay, of the teeth, and the diseases, consequent thereto, and to the human mouth.

This has been satisfactorily proven in numerous instances, during the period of more than two years in which time I have been in the daily habit of using them for that purpose. The pyroliqueous acid, and pyroliqueous, or empyreumatic oil (tar or balsam) it is well known, are obtained by the distillation of wood of any kind, or other vegetable substance, and even wood root, in a close vessel, and to which heat is externally applied, until the wood, or other vegetable matter contained in such vessel, is reduced to a perfect carbon, and yields no further product. The specific properties and uses of the above preparation or mixture, viz. the pyroliqueous acid, and pyroliqueous oil (tar or balsam) however differently modified, is, that, by the highly antiseptic qualities which they possess they counteract the caries in the teeth, allay the pain and irritability in the vessels of the tooth - teeth, loosen the morbid densities, and arouse and restore to a healthy tone the energies of the surrounding parts, when in a state of disease.

The above pyroliqueous acid and oil, then, when used for the purposes specified, either separately or combined, are not only susceptible of, but must necessarily be differently modified, as circumstances may require - hence when applied with a view to counteract a deep & extensive caries, or decay in a tooth or teeth, and to destroy, or allay the great irritability and pain of the parts, - apply the pyroliqueous oil with a very small proportion of

the acid, aromatized with the oil of cinnamon, or other essential oils; to the cavity of the diseased tooth or teeth, on a deposit of cotton or lint; and this is repeated, several times as occasion may require to produce the desired effect —

When applied to correct or counteract a general disposition in the teeth to decay, for scorbutic, ulcerated, or otherwise diseased state of the gums and mouth, I use a saturated solution of the pyroligneous or empyreumatic oil and pyroligneous acid, to which is added three or more parts of water to one of the pyroligneous mixture. With this mixture the mouth is to be gargled twice or thrice each day, or as occasion may require —

These modifications, or mixtures, I denominate the Odontalgic balsam, or odontalgic and antiscorbutic elixir for the teeth and gums —

In fine, what I claim as my peculiar discovery, improvement, or invention and for which I claim a patent is the exclusive privilege of using and rendering, or causing to be used the empyreumatic or pyroligneous oil (tar or balsam) and acid obtained in whatever mode or manner, by the distillation of wood or other vegetable substances, and even wood root, which oil and acid when properly modified, proportioned, or applied, is used for the purpose of arresting or counteracting the caries, or decay, in human teeth, and the diseases consequent thereto and to the human teeth.
